UNITED STATES PATENT OFFICE.

CHARLES MARION BLY, OF TAMPA, FLORIDA.

DESIGN FOR A LAMP STAND.

Application filed April 2, 1926. Serial No. 17,169. Term of patent 3½ years.

To all whom it may concern:

Be it known that I, CHARLES MARION BLY, a citizen of the United States, residing at Tampa, in the county of Hillsborough and State of Florida, have invented a new, original, and ornamental Design for Lamp Stand, of which the following is a specification, reference being had to the accompanying drawings, forming a part thereof.

I claim:

The ornamental design for a lamp stand, as shown.

In testimony whereof I affix my signature.

CHARLES MARION BLY.
